UNITED STATES PATENT OFFICE.

MARTIN C. NEUNER, OF LOS ANGELES, CALIFORNIA, ASSIGNOR TO THE NEUNER SPECIALTY BOOK CO., OF LOS ANGELES, CALIFORNIA, A CORPORATION OF CALIFORNIA.

LOOSE-LEAF BINDER.

No. 883,042.

Specification of Letters Patent. Patented March 24, 1908.

Application filed May 22, 1905. Serial No. 261,549.

To all whom it may concern:

Be it known that I, MARTIN C. NEUNER, a citizen of the United States, residing at Los Angeles, in the county of Los Angeles and 5 State of California, have invented a new and useful Improvement in Loose-Leaf Binders, of which the following is a specification.

This invention relates to binders for loose-leaf records, and the main object of the in- 10 vention is to facilitate the insertion of leaves in the binder.

Another object of the invention is to pro- 15 vide means for permanently locking the binder when it is full or when no more sheets are to be inserted therein.

The accompanying drawings illustrate the invention:

Figure 1 is a perspective of the binder in open position. Fig. 2 is a similar view 20 showing the binder clamp in closed position. Fig. 3 is an end elevation of the clamp portion of the binder in open position. Fig. 4 is a similar view thereof in closed position. Fig. 5 is a perspective of the operating and 25 locking means for the clamp-locking bar. Fig. 6 is a similar view to Fig. 5 showing the operating means removed, leaving the bar in locked condition. Fig. 7 is a fragmentary plan partly in section, of the locking bar 30 case with the bar in position which it occupies when the binder is being used. Fig. 8 is a similar view, showing the position of the bar in permanent locked condition.

1 designates the back member of the 35 binder, the same being formed in round or channel shape, the binder covers 2, 2', being connected by the book-back portion 3 which is secured to said back member 1.

At one side or edge of the back member 1 is pivoted or hinged by pivots 4, a bar 5 carrying studs or pins 6 for engagement with the paper or leaves, the latter being suitably perforated to fit over said pins the pivots 4 extending parallel to the back member to enable the bar 5 to swing transversely to the back and cover members. At the other side or edge of the back member 1 is pivoted or hinged at 7', a member 7 formed as a case or carrier for the locking bar 8 which slides 50 therein and engages the pins 6 to lock the same in closed position. The locking bar 8 has perforations or slots 9 to engage the pins 6, the latter having notches 10 for the reception of the locking bar, and the case 7 having

perforations 11 for the passage of the pins 55 into engagement with the locking bar.

For operation of the locking bar a lever 12 is pivoted to the case 7, and has a cam portion 14, see Fig. 5, which engages in a seat 15 in the locking bar to cause the locking 60 bar to traverse longitudinally in the case 7 when the lever 12 is raised or lowered. When the lever is raised the locking bar is pulled back, leaving the perforations therein in register with the perforations 11, in the 65 case 7, permitting free entry or withdrawal of the pins 6. When the lever 12 is depressed it slides the locking bar along the slot in such manner as to cause the rear edges of openings 9 to engage the notches 10 in the pins 6 and 70 prevent withdrawal of said pins.

A retaining bar 16 may be provided, the same having L-shaped slots or notches 16' whereby the bar may be slipped over the pins 6, and clamp members 17 being pivoted to 75 the said bar 16, and having cam/lugs 18 which may be swung clear of the pin, as shown in Fig. 1 to enable the retaining bar to be slipped up and down on the pins to clamp the paper tightly, or it may be brought into 80 engagement with the pins, as shown in Fig. 2, to clamp said retaining bar tightly in place. In inserting leaves into the binder the hinged bar 5 may be turned back against the cover so that the pins 6 project in position 85 to facilitate placing the leaves thereon. Thence the bar may be turned to cause the pins to cross or bridge the back member, the locking bar being first turned away to enable this movement and being then turned to- 90 ward the pins to engage the same.

It is desirable in some cases to provide for permanently locking the leaves in place after the binder has been filled or the record is completed: For this purpose I have made 95 the pivot 13 of the lever 12 removable; the same consisting, for example, of a screw. A permanent lock for the bar 8 is provided, consisting of a lug or projection 19 extending inwardly from one wall of the case 7. In normal operation of the operating lever 12, the end of the locking bar does not pass this projection and the latter is without effect, but on removing the screw 13 the lever 12 may be removed and the bar may then be pushed in 100 to bring its end beyond the projection 19. This is accomplished by the use of any suitable instrument by the operator. In the nor-

mal or usual operation of the parts the inward projection 19, see Fig. 7, rides on the bar 8, the wall of the case yielding by its elasticity sufficiently to permit this movement, but when the bar 8 is pushed all the way in, as shown in Fig. 8, the wall of the case will resume its natural position bringing the lug 19 in the rear of the bar 8, as shown in Fig. 8, and preventing outward movement of the 10 bar. It will be understood that at this time the binder will be full of paper which will press the locking bar in such a manner as to hold it against the side of the case carrying the projection 19, and this, together with the 15 friction of the parts, will aid in preventing the withdrawal of the bar when it has once assumed this position.

In loose leaf binders, neatness of the completed book is very desirable as well as 20 strength and compactness. By utilizing a round or channel shaped metal back member 1 and hinging the stud or pin bar 5 to the edge of this plate and independently of the binder covers 2, 2', and book-back portion 3, 25 I am enabled to provide a much neater binding as well as a binding of great strength and compactness. Another advantage secured by this construction is avoiding the necessity of the studs or pins 6 projecting through the 30 covers 2, 2'. Furthermore with such construction it is possible to construct account books having the same general shapes and styles of the standard bound books which have no sharp edges or corners to scratch or 35 mark the surfaces upon which they are used. The use of the round or channel shaped metal back member 1 also enables the use of a number of small metal hinge connections between the edge of the member 1 and the plate or bar 40 5, thus securing great strength, which could not be secured if the bar or plate 5 were connected to a flexible portion of the cover so as to form a flexible hinge, and also provides a stiff back for the book relieving the greater 45 portion of the strain, where the book is open and in use, from the pins or studs 6. By

thus hinging the pin bar 5 to the back member 1, it is possible to swing all the leaves on the pins over so they rest flat and admit the ready addition of further leaves without any 50 chance of any leaf slipping off any of the studs or pins 6, such leaves being most readily slipped upon the studs or pins when the latter extend up vertically. Furthermore, the hinging or pivoting of the pin bar 5 obviates any necessity of using open topped slots in the locking-bar case 7. The use of an 55 enclosed case permits of the use of a sliding locking-bar 8 without the necessity of providing a mounting for the latter upon the hinged plate, as by studs and elongated slots. The use of the inclosing case 7 also renders possible the use of concealed means for locking the bar 8 to prevent return movement.

What I claim is:

1. A loose-leaf binder comprising a leaf-engaging member, a movable locking member therefor, an operating means for the locking member having a limited movement, said operating member being removable to allow 70 further movement of the locking member, and means engaging the locking member to lock the same on such further movement.

2. A loose-leaf binder comprising a leaf-engaging member, a locking member therefor, a case wherein the locking member is slidably mounted, a lever detachably pivoted on the case and engaging the locking member to move the same longitudinally a limited distance, the locking member being movable 80 a further distance when the lever is removed, and a projection in the case engaging the locking member on such further movement, to prevent back movement thereof.

In testimony whereof, I have hereunto set 85 my hand at Los Angeles, California this 15th day of May 1905.

MARTIN C. NEUNER.

In presence of—

ARTHUR P. KNIGHT,
JULIA TOWNSEND.
